Attorney.

UNITED STATES PATENT OFFICE.

MORTIMER CAHILL, OF JACKSONVILLE, ILLINOIS.

LIFTING DEVICE.

SPECIFICATION forming part of Letters Patent No. 245,054, dated August 2, 1881.

Application filed February 16, 1881. (No model.)

To all whom it may concern:

Be it known that I, MORTIMER CAHILL, a citizen of the United States, residing at Jacksonville, in the county of Morgan and State of Illinois, have invented certain new and useful 5 Improvements in Lifting Devices; and I do hereby declare that the following is a full, clear, and exact description of the same, reference being had to the annexed drawing, 10 making a part of this specification, and to the letters and figures of reference marked thereon.

This invention has relation to certain new and useful improvements in lifting devices, it being found important, in many places, to have 15 a lever or lifting device which would combine great power, simplicity, and ease of management, together with a self-locking principle, when the object to be raised is either raised to its greatest height or lowered to its resting- 20 point.

It is the object of my invention to provide a device that will successfully embody the above-mentioned features, which I attain by the construction and combination of the several elements illustrated in the accompanying 25 drawing and hereinafter described.

In the drawing, which represents a side elevation of my invention, A is a suitable base, or any frame to which the lifting device may 30 be connected where it is desirable to lift an object easily.

B is an ordinary bar, of metal or other suitable material, which serves as a lever, and is formed with an elongated slot, a.

35 The lever B is pivoted to a suitable short standard, b, and one end of an angle-iron, C, is connected to the lever by means of a rivet or bolt, c, which passes through the elongated

slot a, so that the angle-iron will have the required movement along the slot when the lever is being operated. This angle-iron C, at or near its center, is pivoted to the short standard b, and one end of the angle-iron is pivoted to a link or brace, D, the latter being in turn pivoted to the end of an arm, E, said arm being pivoted to the base A or any other suitable object. By this arrangement of pivoted connections it will be readily seen that as the lever B is brought around to the position shown in broken lines the object connected at x to be 40 raised or lowered will pass the distance described by Figs. 1 and 2, the downward force of which at either point will lock the lever B 45 or hold it in position.

In place of the elongated slot a, a suitable 50 clasp may be attached to the upper end of angle-iron C, the lever B passing through said clasp. This construction will effect the same result and allow the required movement of the lever and angle-iron.

Having now fully described my invention, what I claim as new, and desire to secure by Letters Patent, is—

A lifting device consisting of the lever B, angle-iron C, link or brace D, and arm E, all 55 constructed and arranged in combination with each other substantially as and for the purpose set forth.

In testimony that I claim the above I have hereunto subscribed my name in the presence 70 of two witnesses.

MORTIMER CAHILL.
